PIPE

Toby S. David, Detroit, Mich.

Application October 7, 1953, Serial No. 27,094

Term of patent 14 years

(Cl. D85—8)

To all whom it may concern:

Be it known that I, Toby S. David, a citizen of the United States of America, residing in Detroit, county of Wayne, State of Michigan, have invented a new, original, and ornamental Design for a Pipe, of which the following is a specification, reference being had to the accompanying drawings forming a part hereof.

Fig. 1 is a side elevational view of a pipe, showing my new design;

Fig. 2 is a bottom plan view thereof;

Fig. 3 is a top plan view thereof; and

Fig. 4 is an end elevational view thereof.

Portions of the drawing figures are diagonally lined to indicate transparency.

I claim:

The ornamental design for a pipe, as shown and described.
